CLAIM

I claim the ornamental design for a bottle, as shown and described.

DESCRIPTION

FIG. 1 is a perspective view of a bottle showing my new design.

FIG. 2 is a side view of the bottle viewed from the right side

FIG. 3 is a front view of the bottle of FIG. 1.

FIG. 4 is a rear view of the bottle of FIG. 1.

FIG. 5 is a top plan view of the bottle of FIG. 1; and,
FIG. 6 is a bottom plan view of the bottle of FIG. 1.
